CLAIM

The ornamental design for a suntan lotion applicator, as shown and described.

DESCRIPTION

FIG. 1 is a perspective view of a suntan lotion applicator, showing our new design, with the cap shown closed;

FIG. 2 is a bottom plan view thereof;

FIG. 3 is a right side elevational view thereof;

FIG. 4 is a top plan view thereof;

FIG. 5 is a left side elevational view thereof;

FIG. 6 is a rear elevational view thereof;

FIG. 7 is a front elevational view thereof;

FIG. 8 is a perspective view of a second embodiment of the design of FIG. 1, with the cap shown removed;

FIG. 9 is a bottom plan view of FIG. 8;

FIG. 10 is a right side elevational view of FIG. 8;

FIG. 11 is a top plan view of FIG. 8;

FIG. 12 is a left side elevational view of FIG. 8;

FIG. 13 is a rear elevational view of FIG. 8;

FIG. 14 is a front elevational view of FIG. 8.

*FIG. 4**FIG. 5**FIG. 6**FIG. 7*

FIG. 11**FIG. 12****FIG. 13****FIG. 14**
